UNITED STATES PATENT OFFICE.

STEPHEN F. BRIGGS, OF MILWAUKEE, WISCONSIN, ASSIGNOR TO BRIGGS & STRATTON CO., OF MILWAUKEE, WISCONSIN, A CORPORATION OF WISCONSIN.

LIGHTING AND IGNITION SWITCH.

Application filed March 8, 1915. Serial No. 12,873.

To all whom it may concern:

Be it known that I, STEPHEN F. BRIGGS, a citizen of the United States, and resident of Milwaukee, in the county of Milwaukee and State of Wisconsin, have invented new and useful Improvements in Lighting and Ignition Switches, of which the following is a description, reference being had to the accompanying drawings, which are a part 10 of this specification.

This invention has for its object to provide a switch for controlling the electric lights of an automobile or the like and at the same time constitute a lock for rendering 15 the gas engine ignition ineffective by the removal of the switch key to prevent unauthorized use of the automobile.

Another object of the invention is to provide such a switch capable of dimming 20 the headlights by introducing resistance in series therewith.

Another object of the invention is to perfect details of construction of a switch of this type to render it durable and efficient in 25 use, though inexpensive to manufacture.

With the above and other objects in view the invention consists in the lighting and ignition switch as herein claimed and all equivalents.

30 Referring to the accompanying drawings, in which like characters of reference indicate the same parts in the different views:

Fig. 1 is a sectional elevation of a lighting and ignition switch constructed in accordance with this invention;

Fig. 2 is a rear view thereof;

Fig. 3 is a front view thereof;

Fig. 4 is a rear view thereof with the base removed and showing the key in place in the 40 switch member;

Fig. 5 is a view of the key alone;

Fig. 6 is a sectional plan view showing the arrangement of contacts on the switch base with the relative position of the switch arms shown in dotted lines and representing the 45 "off" position of the switch;

Fig. 7 is a similar view showing the "dim" position of the switch; and,

Fig. 8 is a similar view showing the "on" 50 position of the switch.

Fig. 9 is a diagram of electrical circuits controlled by the switch.

In these drawings 10 indicates a casing which is cylindrical and has an inturned

flange at one end by which it is connected 55 to an ornamental disk-shaped front plate 11, preferably bearing the words, "Off," "Dim" and "On" for indicating the condition of the switch connections in the different positions of a switch key 12, fitting in a 60 central opening of the plate. A switch base 13, consisting of a disk of insulating material fitting in the end of the casing 10 and held in place by screws 14, has a metal sleeve 15 embedded centrally therein and projecting 65 above the recessed upper surface of the base where it is slotted to receive a flat spring 16 mounted on a post 17 which on the rear of the base is connected by a metal strip 18 with a binding post 19. This flat spring 70 after making a reverse bend enters the slot of the tube and then engages a contact post 20 which forms a binding post on the back of the base, the binding posts 19 and 20 being adapted for connection with the terminals 75 of a magneto for grounding or short circuiting the magneto by the engagement of the spring 16 with the contact post 20 when the key is removed. The key 12 has a reduced cylindrical neck portion 21 and a conical enlarged tip 22 which serve to force the contact spring 16 away from the contact post 20 when the key is inserted in the switch, the spring also serving to retain 80 the key in place by engaging the enlarged tip thereof at the reduced neck portion 21. The key has an operating portion 23, rectangular in cross section, and preferably oblong to fit within a correspondingly shaped opening in a disk-like switch member 24 of 85 insulating material which bears against the underside of the front plate 11 between the shoulders formed by the inturned flange of casing 10 where it is held by the spring pressure of the spring arms of a spring contact 90 spider 25 which is secured to the underside of the switch member 24 and bears with the convex outer ends of its radial spring arms against the upper surface of the insulating base 13. The center of the spider 25 has an 95 opening sufficiently larger than the opening through the switch member 24 to be protected from contact with the key 12, and the spider is preferably in duplicate so as to give greater durability to the flexible spring 100 arms. The top of the base 13 is provided with a circular series of regularly spaced recesses or depressions forming seating cav- 105

ties for the convex ends of spring contact arms 25, and certain of these depressions are formed in the ends of metal bushings forming stationary contacts 26, 27 and 28. These 5 stationary contacts form binding posts and the binding posts 26 and 28 have the terminals of a resistance unit 29 connected therewith, such resistance unit being here shown in the form of a wire wound tube with an 10 insulating coating, though it may be of any form.

In connecting up the switch the binding post 19 is connected to the ground at 30, and the binding post 20 by a wire 31 with 15 one terminal of the armature of a magneto 32 whose other terminal is grounded at 33. The binding post 26 is connected by a wire 34 with one or more headlights 35 which are also connected by a wire 36 with one 20 terminal of a battery 37 whose other terminal 38 is connected to binding post 27, while binding post 28 is connected by a wire 39 with a taillight 40 which is also connected by a wire 41 with wire 36 leading 25 to the battery. In the "off" position of the switch, as shown in Fig. 6, the only stationary contact engaged by one of the spring arms 25 is battery connected contact 27, but in the "dim" position of the 30 switch, shown in Fig. 7, both the contact 27 and the contact 28 are engaged by the spring arms, thus establishing a circuit from one terminal of the battery through wire 38, contact 27, contact arms 25, contact 28, 35 wire 39, taillight 40, wires 41 and 36, to the other terminal of the battery. Also, a circuit is established through the headlights with the resistance coil 29 in series therewith as follows: starting with one terminal 40 of the battery 37 wire 38, contact 27, spring contacts 25, contact 28, resistance 29, contact 26, wire 34, headlights 35, and wire 36, to the other terminal of the battery. In 45 this position of the switch, therefore, the tail light and the headlights are burning, but the headlights are dimmed. In the "on" position of the switch, as shown in Fig. 8, all three contacts 27, 26 and 28 are engaged by the contact arms so that the circuit 50 through the taillight from contact 28 is the same as before, but the circuit through the headlights is without the resistance 29 in series therewith, for the contact arm 25 engaging contact 26 establishes a circuit 55 through the headlights direct, this circuit being from one terminal of the battery 37, wire 38, contact 27, contact arms 25, contact 26, wire 34, headlights 35, and wire 36 to the other terminal of the battery. 60 In any position of the switch the presence of the key 12 in the switch serves to hold the contact spring 16 out of engagement with the contact post 20, and thus open the short circuit connection for the magneto 65 armature so that it may produce its usual

office in the ignition circuit 42. As illustrated, the ignition circuit 42 includes primary winding 43 of an induction coil grounded at 44, the secondary winding 45 of which is grounded at 46 and is connected 70 by a wire 47 with a distributor 48, the contacts 49 of which are connected with the respective grounded spark plugs 50 of the engine.

Whenever the switch key is removed from 75 the switch the spring contact 16, by engaging the contact post 18, grounds or short circuits the armature of the magneto, thus rendering it ineffective for producing ignition and so preventing unauthorized use of 80 the car. In order that the switch may be confined to the three positions referred to, the switch member 24 has a pair of stop pins 51 projecting radially therefrom and adapted to contact with a stationary stop 85 pin 52 on the rim of the casing 10. The shape of the ends of the contact arms and the shape of the recesses into which they fit is such that the switch is firmly held in any of its operative positions, and spacing posts 53 on the switch member 24 by 90 engaging the base 13 prevent these parts being positioned too close together for proper operation of the spring arms in assembling 95 the device.

The switch of this invention forms a simple and inexpensive means for controlling the lighting circuits, as well as the ignition circuit, giving to the headlights either a full, strong light, or a dim light, and lighting the tail light in either position, while permitting the key to be removed in any position of the switch to lock the car by rendering the ignition circuit ineffective. 100

When battery ignition is used the spring contact 16 is so disposed with relation to the contact post 20 that it contacts therewith when the key is inserted and springs away therefrom when the key is removed, it being only necessary to bend the end of the 110 spring to engage the contact post on the other side thereof to effect this change.

It will be understood that the automobile switch of this invention constitutes a lighting switch by means of the co-operating contacts 25, 26, 27 and 28, and an ignition switch by means of the co-operating contacts 16 and 20, wherein the removable plug or key 12 constitutes a removable actuating member for the ignition switch and wherein the insulating disk 24 engaged with the square portion of the removable key constitutes a means controlled by the actuating member for operating the lighting switch. 115

It will also be understood that the automobile switch of this invention is one in which the contacts 16 and 20 control an ignition circuit and is one in which the contacts 25, 26, 27 and 28 control an electric lighting circuit including a plurality of 120 125 130

lights 35 and 40, and this single switch construction for controlling the current in both of said circuits will in one position maintain the lights 35 and 40 brilliant and during a part of the operation thereof will dim some of the lights by including resistance 29 in series with the lights 35.

It is obvious that the particular arrangement of stationary contacts and spring arms 10 is not essential, as the desired results may be obtained with various other arrangements, as for instance the dimming of the headlights may be effected by a connection in which the headlights are included in 15 series with each other, or by making connections for auxiliary headlight lamp bulbs, and connections may be provided for side lights with either dim or on positions of the switch, or both. In the manufacture of the 20 switch it may be desirable to construct the spring spider with arms corresponding to the various recesses into which they fit and then such spring arms as are not essential for the particular arrangement of the switch 25 desired may be removed.

The dimming resistance coil 29 when in series with the headlights serves to check the flow of current therethrough to such an extent as to dim them, but when this resistance is in series with the tail-light, as when 30 connection is made between the battery terminal 27 and the headlight terminal 26 without direct connection with the tail-light terminal 28, it is ineffective for materially 35 changing the brilliancy of the tail-light because of the relatively greater resistance of the tail-light. Thus when it is inconvenient to provide a switch arm for the tail-light contact in the "on" position of the switch, 40 the same may be dispensed with and the tail-light will receive its current supply through the dimming coil.

What I claim as new, and desire to secure by Letters Patent is:

45 1. A switch, comprising a base having contacts, a rotary switch member having contact means for engaging the contacts, a removable key for engaging and turning the switch member, and other switch contacts 50 actuated by the insertion of the key.

2. An automobile lighting and ignition switch, comprising a casing, an insulating base therein having stationary contacts for connection with the battery and the automobile lights, an insulating switch member 55 within the casing, spring arms carried thereby and engaging the base member and forming spring contacts to engage the stationary contacts, said switch member having an opening therethrough, a removable key fitting in the opening of the switch member, and a pair of ignition contacts one of 60 which is spring actuated and engages the key for holding the key in place and for 65 controlling the ignition circuit.

3. An automobile lighting and ignition switch, comprising a casing, an insulating base therein having stationary contacts for connection with the battery and the automobile lights, a switch member within the 70 casing, spring arms on the switch member for engaging the base and forming spring contacts for engaging the stationary contacts, a key fitting in the opening of the switch member for turning the same, said 75 key having a contracted neck portion, a spring engaging the contracted neck portion of the key for holding the key in place, said spring being moved out of position by the insertion of the key, and a contact post engaged by the spring in one position thereof. 80

4. An automobile lighting and ignition switch, comprising a casing, a base fitting therein, stationary contacts on the base for connection with the battery and the automobile lights, a switch member, spring arms carried thereby and bearing on the base to form spring contacts for engaging the stationary contacts, a tube in the base, a key fitting in an opening of the switch member 85 and in the tube and having a contracted neck portion, a spring projecting through an opening in the side of the tube and engaging the contracted neck portion of the key, and a contact post engaged by the spring in 90 one position thereof. 95

5. An automobile lighting and ignition switch, comprising a cylindrical casing with an inwardly projecting flange at one end thereof, a front plate secured to the flanged 100 end of the casing, an insulating base fitting in the other end of the casing and having stationary contacts for connection with the source of current supply and the automobile lights, an insulating disk forming a 105 switch member bearing against the back of the front plate and positioned between the edges of the flange of the casing, spring arms on the switch member engaging the base and forming spring contacts for 110 engaging the stationary contacts, a key passing through an opening in the front plate and fitting in an opening in the switch member and having a contracted neck portion, a tube in the base receiving the end of the 115 key, a contact spring on the base passing through an opening in the side of the tube for engaging the contracted neck portion of the key, and a contact post engaged by the contact spring in one position thereof. 120

6. An automobile lighting and ignition switch, comprising a rotary switch member adapted to establish connections for controlling the automobile lights, a removable key for turning the switch member, and ignition controlling means dependent upon the attachment of the key for rendering the ignition inoperative when the key is withdrawn. 125

7. In a combination switch, a removable handle, switch contacts controlled by the at- 130

- tachment of the handle, and other switch contacts controlled by the turning of the attached handle.
8. A lighting switch and an ignition switch for automobiles or the like, a removable actuating member for said ignition switch, and means controlled by said actuating member for operating said lighting switch.
10. 9. In a combination lighting and ignition switch, a key controlled lighting switch, and an ignition switch actuated by the introduction of the key.
10. In a combination lighting and ignition switch, a key controlled movable lighting switch, and a spring-pressed member adapted to be moved by the insertion of the key to render an ignition circuit effective.
11. An automobile lighting and ignition switch, comprising an oscillating switch member adapted to establish connections for controlling the automobile lights, a removable key for turning the switch member, and ignition controlling means dependent upon the attachment of the key for rendering the ignition inoperative when the key is withdrawn.
12. A switch comprising a base having contacts, a rotary switch member having contact means for engaging the contacts, a removable key for controlling the actuation of said switch member, and other switch contacts actuated by the removable key.
13. In a combination lighting and auxiliary switch, a key controlled lighting switch, and an auxiliary switch actuated by the key.
14. A switch comprising a base having
- contacts, a rotary switch member having contact means for engaging the contacts, a removable key for controlling the actuation of said switch member, and other switch contacts actuated by the key.
15. A pair of electrical switches and a removable common actuating means therefor, said means actuating one of said switches by a movement in a longitudinal direction and the other of said switches by a movement in a rotary direction.
16. An ignition switch and a lighting switch for automobiles, an enclosing casing therefor, and a removable common member extending through said casing for operating both of said switches, said member operating the ignition switch by a movement in a longitudinal direction and the lighting switch by a movement in a rotary direction.
17. A lighting switch and an ignition switch for automobiles or the like, and a removable common actuating member for independently operating said switches.
18. An ignition switch and a lighting switch for automobiles, said lighting switch having a plurality of positions, an enclosing casing for said switches, a removable common operating member for said switches, said member operating the ignition switch by being partly drawn or inserted into the enclosing casing and the lighting switch by being rotated.
- In testimony whereof, I affix my signature, in presence of two witnesses.
- STEPHEN F. BRIGGS.
